INVENTOR
Charles A. Bayler,

BY

John J. Thompson
ATTORNEY

UNITED STATES PATENT OFFICE.

CHARLES A. BAYLER, OF YORK, PENNSYLVANIA.

WHEELED TRAY.

1,038,267.

Specification of Letters Patent. Patented Sept. 10, 1912.

Application filed January 23, 1912. Serial No. 672,951.

To all whom it may concern:

Be it known that I, CHARLES A. BAYLER, a citizen of the United States, residing at York, in the county of York and State of Pennsylvania, have invented certain new and useful Improvements in Wheeled Trays, of which the following is a specification, reference being had thereto to the accompanying drawing.

10 This invention relates to a wheeled tray or rack of the class intended for the transportation of dishes, and such like, from room to room; and the invention is intended particularly for household purposes.

15 While I am aware that there are devices now in use for this purpose, they are so constructed as to be unreliable and dangerous, as they are apt to tip over; and there is no provision made to prevent the trays 20 from tipping.

The object of my invention is to provide a device of this class that shall be cheap, durable and efficient, containing few parts, and so constructed and proportioned as to 25 minimize the danger of upset.

Another object of the invention is to provide a device that shall be easily folded for transportation.

With these and other objects in view, my 30 invention consists in certain construction and combination of parts as will hereinafter be described and claimed in the annexed specification, and illustrated in the accompanying drawings which form a part of 35 this application, and in which like figures of reference refer to corresponding parts in all of the views; but it is fully understood that while I have here described my invention as shown, that I do not confine myself 40 to the exact design, as slight changes may be made in the construction and arrangement of the several parts without departing from the spirit of the invention.

In the drawings:—Figure 1, is a perspective view of the device set up. Fig. 2, is a top plan view of the same with the trays removed. Fig. 3, is an elevation, showing the device knocked down for packing. Fig. 4, is a partial detail view of the front wheel 45 swiveling means, shown in section. Fig. 5, is a partial sectional detail view of the rear wheel attaching means. Fig. 6, is a partial detail view of the tray attaching means.

Referring to the drawings: the frame comprises the hollow rear posts 1, and the front post 2, of piping or suitable material. The

rear posts 1, are joined together in a rigid manner by the upper and lower braces 3, 26 and 4, respectively, which are approximately U-shaped, and embrace the posts 1, to which they are secured by the bolts or rivets 5. To the forward ends of said braces 3, and 4, are secured the ends of the side frames 6, and 7, by the bolts 8, 9, and 10; said side frames 6, and 7, being approximately V-shaped and embracing the front post 2, at the apex of the V, and secured thereto in a detachable manner by the bolts 25. The rear wheels 11, are mounted upon axles 12, which are screw-threaded into the sides of the posts 1, near the lower end thereof, and secured by the lock-nut 13. The front wheel 14, is mounted in the yoke 15; the shank 16, of said yoke 15, is swivelly mounted in the lower end of the post 2, in the following manner:—The lower end of said post 2, is provided with a coupling 17, and a nipple 18. The shank 16, extends upward through the nipple 18, and a washer 19, is placed upon the upper end thereof, within said coupling 17, and resting on the upper end of said nipple 18, and a pin 20, is placed through the end of said shank 16, upon said washer 19, and in this manner a swivel is obtained.

For securing the trays in a detachable manner, the upper tray 21, is provided with depending studs 22, secured thereto which enter the upper ends of the posts 1, and 2, thus securing the tray; which is further prevented from tipping by the side frame 6, which is curved outward to conform to the shape of the tray and support it near its edge.

The lower tray 23, rests upon the lower 95 side frame 7, in like manner, lateral movement being prevented by the rear posts 1, and a yoke 24, secured to the front of said tray 23, and engaging the front post 2.

To fold the device for shipment, the side 100 frames are detached from the front post 2, and the bolts 8, removed, which will allow the side frames 6 and 7, to fold as shown in Fig. 3.

Having thus described my invention what 105 I claim as new and desire to secure by Letters Patent is:—

1. In a device of the class described, the combination with a front and rear post, of outwardly curved non-resilient side frames 110 secured thereto, trays mounted on said frames, studs depending from the bottom of

the upper tray entering the upper ends of said posts.

2. In a device of the class described, the combination with a front and rear post, 5 having wheels mounted upon the lower ends thereof, of an upper and a lower non-resilient frame secured to said posts, the sides of said frames curved outwardly, trays resting upon said frames, studs secured to and 10 depending from the lower surface of the upper tray entering the upper ends of said posts, and means for mounting one of said wheels in a swiveling manner to said front post.

15 3. In a device of the class described, the

combination with upright hollow posts, non-resilient frames secured thereto and detachable trays resting upon said frames, of means for preventing the accidental tipping of said trays, comprising studs secured 20 thereto and entering the upper ends of said posts, said frames outwardly curved and adjacent to the outer edge of said trays.

In testimony whereof I affix my signature in presence of two witnesses.

CHARLES A. BAYLER.

Witnesses:
